DESIGN FOR A LAPEL ORNAMENT OR THE LIKE

Sol P. Kaufman, New York, N. Y.

Application December 16, 1940, Serial No. 97,359

Term of patent 3½ years

To all whom it may concern:

Be it known that I, Sol P. Kaufman, a citizen of the United States, residing at New York city, in the county and State of New York, have invented a new, original, and ornamental Design for a Lapel Ornamental or the Like, of which the following is a specification, reference being had to the accompanying drawing, forming part thereof.

Fig. 1 is a front view of a lapel ornament or the like, showing my new design.

Fig. 2 is a top plan view thereof.

I claim:

The ornamental design for a lapel ornament or the like, substantially as shown.

SOL P. KAUFMAN.
